UNITED STATES PATENT OFFICE.

ORA A. COLBY, OF LARIMER, PENNSYLVANIA, ASSIGNOR TO WESTINGHOUSE ELECTRIC & MANUFACTURING COMPANY, A CORPORATION OF PENNSYLVANIA.

ELECTRIC FURNACE FOR HEATING RIBBONS AND BARS.

1,347,895.

Specification of Letters Patent.

Patented July 27, 1920.

Application filed September 16, 1918. Serial No. 254,221.

To all whom it may concern:

Be it known that I, ORA A. COLBY, a citizen of the United States, and a resident of Larimer, in the county of Westmoreland 5 and State of Pennsylvania, have invented a new and useful Improvement in Electric Furnaces for Heating Ribbons and Bars, of which the following is a specification.

My invention relates to electric furnaces 10 which are employed for continuously heating bars and ribbons that are fed to automatic forging mechanisms, and it has for its object to provide means whereby heat is supplied to the bars or ribbons in the proportions demanded by the varying temperatures of such bars or ribbons at the various points in their paths of movement through the heating chamber of the electric furnace.

In electric furnaces of the character above 15 designated, it is desirable to have means associated with the furnace whereby the bar or ribbon shall be supplied with more heat at the point of entrance to the furnace than at the point of exit therefrom because of the fact that the metal serves to cool the zone at the entrance of the heating chamber to a greater degree than it does at other points farther along in its path of movement.

Another object of my invention is to provide heating means for such bars which will be compactly contained and, at the same time, will permit the heating elements to be easily removable for purposes of repair or substitution.

For a better understanding of my invention, reference may be had to the accompanying drawing in which:

Figure 1 is a horizontal, sectional view, taken on line I—I of Fig. 2, of a furnace 20 constructed in accordance with my invention, and Fig. 2 is a vertical sectional view taken on line II—II of Fig. 1.

Referring more particularly to the drawing, the furnace is shown as comprising a 25 body portion 1 supported on standards 2 and 3. Extending lengthwise through the furnace, is a passage 4 which is inclosed on all sides, the ceiling of the same consisting of a plurality of silicon carbide resistors 5.

The resistors 5 are supported on two rows 30 of silicon carbide blocks 6—6 which constitute the side walls of the passage 4. The main portion of the furnace body is composed of blocks 7 of refractory material,

and is provided with two wells 8—8 that are 55 filled with granular conducting material to constitute conducting members between the resistors 5 and terminals 9—9.

Referring now to Fig. 1, it will be observed that the row of resistors 5 is broken 60 at a point between the entry and exit ends of the chamber 4 by a wall of fire-brick 10, and that separated sections of the transversely-extending resistor blocks are supplied with current by means of separate 65 terminals 9. For purposes of illustration, it is assumed, in the description hereinafter given of the operation of the furnace, that the lower end of the chamber 4, as shown in Fig. 1, is the entry end, while the other end 70 constitutes the exit end for such metallic bars or ribbons as it is desired to heat.

Having now described a furnace constructed in accordance with my invention, the operation thereof is as follows:

The bar or ribbon to be heated is fed into the passage 4 and the resistors comprising the ceiling of the portion immediately adjacent to the entry are supplied with a relatively greater volume of current than the 80 section at the exit end of the chamber. By this means, more heat is directed upon the cold bar near the entrance than is applied at the exit end, thus maintaining a uniform 85 temperature throughout the entire length of heating chamber, a condition which promotes efficient operation of the heating element which overlies the treating chamber.

Moreover, it will be observed that, since the wells 8—8 are filled with granular material, renewal of this portion of the conducting path between the terminals and the resistors is a matter of little difficulty. Again, the interior portions of the terminals are kept covered and out of contact with the 95 air, thereby preventing deterioration of the same.

Moreover, in a furnace in which the terminals are disposed as herein illustrated, they are located a considerable distance 100 from the hottest portion of the furnace, namely, the resistors 5. In addition, they are positioned in this manner in order that repairs may be easily made thereto by the simple expedient of lifting off the top row 105 of fire bricks.

Again, the location of the resistor 5 in intimate contact with the material in the

two wells 8 and transversely across the heating chamber insures a minimum amount of arcing and other undesirable electric disturbances.

- 5 The disposition of the resistor above the heating chamber is also important because, otherwise, the bar or ribbon would be chemically acted upon by reason of contact with the hot resistor.
- 10 While I have described but one embodiment of my invention, it is apparent that many modifications therein may occur to those skilled in the art and I desire, therefore, that only such limitations shall be placed thereon as are imposed by the scope of the prior art or are specifically set forth in the appended claims.

I claim as my invention:

1. In an electric furnace, the combination with a heating chamber, of a resistor forming the roof of said chamber, supporting means associated with said resistor to provide said heating chamber with a rectangular cross section, said resistor being adapted to be made hotter at one portion than at another.

2. In an electric furnace, the combination with a heating chamber, of a resistor overlying said chamber, supporting means associated with said resistor to provide said heating chamber with a rectangular cross section, said supporting means being partially of electrical conducting material whereby three sides of said rectangular cross-sectional chamber may be utilized for heat emission, and means whereby said chamber may be made hotter at one portion than at another.

3. In an electric furnace, the combination with a heating chamber, of a resistor constituting the top of said chamber, terminal electrodes, granular thermal-insulating, electrical-conducting material interposed between said resistor and said electrodes, and means whereby more current may be supplied to one portion of said resistor than to another portion thereof.

4. In an electric furnace, the combination with a continuous heating chamber, of a discontinuous resistor forming the roof of said chamber, said overlying resistor comprising a plurality of bricks arranged transversely with respect to said heating chamber, said resistor being adapted to be

made hotter at one portion than at another.

5. In an electric furnace, the combination with a heating chamber, of a resistor overlying said chamber and comprising a plurality of conducting blocks extending across the top of said heating chamber, supporting means associated with said resistor blocks so arranged that said chamber is in the form of a box-like passage of appreciable length, terminal electrodes, granular thermal insulating electrical-conducting material interposed between said resistor and said electrodes, one portion of said resistor being adapted to be made hotter than another portion.

6. In an electric furnace, the combination with a heating chamber, of a resistor overlying said chamber and comprising a plurality of conducting blocks extending across the top of said heating chamber, supporting means associated with said resistor blocks so arranged that said chamber is in the form of a box-like passage of appreciable length, said heating chamber being continuous but said resistor being discontinuous, one portion of said resistor being adapted to radiate more heat than another portion.

7. In an electric furnace, the combination with a heating chamber, of a resistor forming the roof of said chamber and comprising a plurality of conducting blocks, side and bottom walls so arranged that said chamber is in the form of a box-like passage of appreciable length, said resistor being in two portions, that portion of the resistor overlying the entrance of said chamber being adapted to radiate more heat than that portion adjacent the exit.

8. In an electric furnace, the combination with a continuous heating chamber, of a discontinuous resistor forming the roof of said chamber, a source of energy supply for said furnace, that portion of said resistor adjacent the entrance of said heating chamber being adapted to derive more current from said source of energy supply than that portion adjacent the exit of said chamber.

In testimony whereof, I have hereunto subscribed my name this 30th day of Aug., 1918.

ORA A. COLBY.
